UNITED STATES PATENT OFFICE

LERoy TABOR, OF RIVERTON, NEW JERSEY, AND FRANK R. WALLACE, OF PHILADELPHIA, PENNSYLVANIA, ASSIGNORS TO THE TABOR MANUFACTURING COMPANY, OF PHILADELPHIA, PENNSYLVANIA, A CORPORATION OF PENNSYLVANIA

ADJUSTABLE HINGED YOKE FOR SQUEEZING MACHINES

Application filed March 6, 1931. Serial No. 520,609.

The device which forms the subject of our invention is an adjustable, hinged yoke or squeezing abutment which is used on a jarring and squeezing machine or on a plain squeezing machine for making sand molds or for other purposes to which the principle may be applied.

Our device consists of a body, means for exerting pressure to make sand molds, a support pivotally mounted on said body, a yoke pivotally mounted in said support, a head movably mounted in one end of said yoke, a roller mounted for rotation in the opposite end of said yoke, a combined guide and stop member on said base cooperating with said roller, a counterbalance spring interposed between said support and said base and a spring interposed between said support and said yoke to yieldingly retain them in their normal relative position.

For a further exposition of our device reference may be had to the annexed drawing and specification at the end whereof our invention will be specifically pointed out and claimed.

In the drawing,

There is disclosed a side elevation of our device with parts broken away.

In the embodiment of our invention chosen for illustration in the drawing, the device is shown as consisting of a base 1 which may be mounted so as to be portable on wheels 2 if so desired. If it is not desired to incorporate this feature of portability wheels 2 may be omitted. Base 1 may, if desired, carry a jarring table 3 upon which the mold is made and which moves upwardly in the usual manner for performing the squeezing operation, when air is admitted under the squeezing piston (not illustrated in detail as it is well known in the art) contained within the base 1 in the manner usual in this type of machine.

Base 1 also carries a support 4 which is pivotally connected thereto by means of pins 5 or in any other suitable manner. At its upper end support 4 is forked or otherwise suitably shaped to provide a bearing for a pin or pins 6 by means of which yoke 7 is pivotally mounted on support 4.

At one end yoke 7 has a squeezing head 8

adjustably mounted therein. Hole 9, in yoke 7, and holes 10 in head 8, provide means for adjusting the position of head 8 relative to yoke 7 by passing a pin or other element through a pair of these holes. As will be seen in the drawing head 8 is located opposite jarring table 3 so that the mold is squeezed between jarring table 3 and head 8. At the opposite end from head 8 yoke 7 carries a roller 11 pivotally mounted therein. At this end yoke 7 also has an end 12 suitably shaped for engagement with a stop member.

This stop member is provided by the combined guide and stop element which may consist of a screw 13 mounted in base 1 and which in turn carries guide element 14. Guide element 14 carries adjusting screw 15 which locates end 12 of yoke 7 in proper horizontal relation to stop pin 13.

Support 4 and yoke 7 are yieldingly retained in their relative normal position by a spring 16 which bears on a collar 17 carried on bolt 18. Bolt 18 is pivotally connected at its opposite end to support 4 by means of pin 19.

Between support 4 and base 1 there is provided a counterbalance spring 20 which bears at one end on a collar 21 pivotally mounted on base 1 and at its opposite end bears on housing 22 which is carried by shaft 23 which in turn is pivotally connected to support 4 by pin 24.

The operation of our device is as follows: When the jarring and squeezing operations of the machine are finished and a finished mold is located in the machine the operator pushes yoke 7 back causing support 4 to pivot about pins 5. This causes roller 11 to slide for a short distance horizontally on guide 14, spring 16 expanding during this movement and permitting yoke 7 to pivot relative to support 4 about pivot 6. This movement carries end 12 of yoke 7 clear of pin 13 and upon further rearward movement of yoke 7, roller 11 travels down guide 14 and moves free thereof. During this pivotal motion of support 4 and yoke 7 spring 20 is compressed and serves to counterbalance the weight of head 8. The center of gravity of head 8 is always maintained to the left of pivot 5, as

seen in the drawing, so that head 8 tends to return to position over jarring table 3. In the return movement of support 4 and yoke 7 roller 11 enters beneath guide 14 due to the curved shape of the end of the guide 14. Spring 16 again permits relative movement between support 4 and yoke 7. Roller 11 moves upward and then inward on guide 14 until end 12 of yoke 7 is located in the proper horizontal position abutting screw 13 because of its lateral engagement with screw 15.

We do not intend to be limited in the practice of our invention save as the scope of the prior art and of the attached claims may require.

We claim:

1. A squeezing machine including a base, a support, a yoke pivotally mounted on said support, said yoke having a portion adapted to withstand the squeezing pressure, and a stop member on said base cooperating with the end of said yoke to withstand said squeezing pressure.

2. A machine including in combination a base, means on said base for exerting the squeezing pressure for forming sand molds, a support pivotally mounted on said base, a yoke pivotally mounted on said support and having at one end a portion adapted to cooperate with said squeezing means and to withstand the pressure thereof and having at its opposite end a face, stop means on said base cooperating with the face of said yoke, and guide means for guiding said face into and out of abutment with said stop means.

3. A machine including a base, means on said base for exerting a squeezing pressure for making sand molds, a support pivotally mounted on said base, a yoke pivotally mounted on said support and having means cooperating with said squeezing means and adapted to withstand the squeezing pressure and having at its opposite end a face, a stop on said base cooperating with the face of said yoke to withstand the squeezing pressure, cooperating means guiding the face of said yoke into and out of abutment with said stop, and means for yieldingly retaining said yoke and said support in their relative normal position.

4. A machine including a base, squeezing means on said base for making sand molds, a support pivotally mounted on said base, a yoke pivotally mounted on said support and having a portion adapted to cooperate with said squeezing means and to withstand the squeezing pressure and having at its opposite end a face, a stop member on said base cooperating with the face of said yoke to withstand the squeezing pressure, means for guiding the face of said yoke into and out of engagement with said stop, means for yieldingly retaining said yoke and said support in their relative normal position, and counterbalancing means interposed be-

tween said support and said base for counterbalancing the weight of that portion of the yoke which receives the squeezing pressure.

5. A machine including in combination a base, squeezing means mounted on said base for making sand molds, a support pivotally mounted on said base, a yoke pivotally mounted on said support and having a portion cooperating with said squeezing means and receiving the squeezing pressure thereof and having at its opposite end a face, a stop on said base cooperating with the face on said yoke to receive the squeezing pressure, a roller mounted on said yoke adjacent said face, and guide means cooperating with said roller for guiding said face into and out of engagement with said stop.

6. A squeezing machine including in combination a base, means mounted on said base for exerting the squeezing pressure to form sand molds, a support pivotally mounted on said base, a yoke pivotally mounted on said support, a head adjustably mounted in one end of said yoke for cooperation with said squeezing means to receive the squeezing pressure, a face on the opposite end of said yoke, a stop on said base cooperating with said face on said yoke to receive the squeezing pressure, a roller mounted on said yoke adjacent said face, a guide mounted on said base for guiding said roller to guide said face into and out of engagement with said stop, a spring yieldingly retaining said yoke and said support in relative normal position, and a spring between said support and said base for counterbalancing the weight of said head.
